UNITED STATES PATENT OFFICE.

EDWARD A. SMITH, OF NEW YORK, N. Y.

PROTECTING DEVICE FOR SHIPS.

1,338,706.

Specification of Letters Patent.

Patented May 4, 1920.

Application filed July 7, 1917. Serial No. 179,109.

To all whom it may concern:

Be it known that I, EDWARD A. SMITH, a citizen of the United States, residing at New York, in the county of New York and 5 State of New York, have invented certain new and useful Improvements in Protecting Devices for Ships, of which the following is a specification.

My invention relates to an improvement 10 in devices for protecting ships against torpedo attack, and from mines, whether floating or fixed, and comprises means whereby the torpedo or mine will be exploded, if at all, before reaching the ship, or may be sal- 15 vaged intact.

In general, my device comprises a number of small auxiliary boats carried by the ship, and connected to each other by chains or metal ropes. These boats are adapted to 20 be lowered from the ship simultaneously, or independently. Each boat has its own propelling and steering apparatus, so that when they are in the water, they are propelled by their own power away from the 25 side of the ship, to form a protecting barrier about her. These auxiliary boats will be propelled at a speed equal to that at which the ship is traveling, or a little in excess of that speed, so as not to impede the pro- 30 gress of the ship at all. Carried by each boat are electromagnets. I have shown a pair carried by each boat, extending into the water below the bottom of the boat, to which the chains or ropes connecting the boats are 35 fastened, and also magnetized, these chains being spaced apart, but close enough together to prevent a torpedo or mine passing through. A torpedo or mine upon entering 40 the field of the magnets or their connecting chains, will be attracted thereto and explode, either by contact or by the magnetic force acting on the exploding mechanism of the torpedo or mine. This will merely 45 destroy one or more of the boats, without injuring the ship. Of course, the boats can be readily replaced, as spare boats will be carried by the ship, and the controlling mechanism for the boats is such that a new boat can be placed in the water without 50 disturbing the boats which have already been launched. Should the torpedo or mine not explode it may be salvaged intact.

Referring to the drawings accompanying this application, Figure 1 is an eleva-

tion of a ship with the auxiliary boats in 55 the water; Fig. 2 is a plan view of the apparatus of Fig. 1, showing in full lines the position of the boats as they strike the water, and in dotted lines their position when in operation; Fig. 3 is a part sectional 60 elevation of one of the auxiliary boats, showing the propelling and steering apparatus, and the magnets carried by the boats; Fig. 4 is a plan of one of the auxiliary boats; Fig. 5 is a section through one of 65 the boats, showing the method of attaching the magnets thereto, and the construction of the hull of the boat; Fig. 6 is an elevation of one of the booms by which the boats are lowered, and raised; Fig. 7 is a section 70 of the mechanism for holding the booms up against the side of the ship when the boats are out of the water; Fig. 8 is a wiring dia- 75 gram showing the various controlling circuits of the system; and Fig. 9 is a view of the brake mechanism for the hoisting motors.

Throughout the drawings, like characters of reference designate like parts.

Referring to the drawings in detail, S 80 designates a ship which it is desired to protect against torpedo attack. 2 designates a series of small auxiliary boats, which are carried by the ship, these boats being decked over as shown in Fig. 5, and may, when 85 out of the water, be kept on the deck of the ship, or merely against the side of the ship, or any other position that may be found desirable. Each boat carries a pair of elec- 90 tronmagnets, 3, 3, waterproofed, and prefer- 95 ably shaped as shown in plan in Fig. 4, so as to offer the least possible resistance to being forced through the water, these magnets being secured to the bottom of each boat by means of bolts 4, 4, and extending down into the water to any desired depth. The boats are secured to each other by means of chains 5 or wire rope, as many as may be found practicable, and placed close together so as to prevent a mine or 100 torpedo from passing between them, these chains being secured to the magnets by snap hooks 6, so that in the event of any of the boats 2 being destroyed, it will be an easy matter to replace it. The magnets on each 105 boat are connected together also, by means of chains or wire ropes 5^a, attached to the magnets by snap hooks 6'. If desired,

chains 7 may be secured to the hulls of the boats also. Each boat carries an electric motor 8, the armature shaft 9 of which is connected to propellers 10. A rudder 11, 5 is also carried by each boat, and is controlled by a tiller 12, which in turn is held in adjusted position by a pin 13. In putting the boats in the water, the rudders will be set at the proper angle to maintain the 10 boats away from the side of the ship any desired distance. Hoisting cables 15 are secured to each boat by means of chains 14, these hoisting cables passing over pulleys 16 carried at the outer end of booms 17, 15 preferably telescopic, which are pivotally secured to the hull or upper works of the ship at 18. The hoisting cables pass over pulleys 19 and 20 carried by the arms 21 of the booms, and up over the rail of the 20 ship and around drums 22, driven by electric motors 23 carried on the deck of the ship. When the apparatus is not in operation, the booms 17 will lie up against the side or upper works of the ship as shown 25 in Fig. 6, being held in position by means of the latch mechanism illustrated in Fig. 7, which comprises the pivoted latch 24, carried in housings 25 secured to the side of the ship, the latches being held in operative 30 position by means of springs 26. When it is desired to release the booms to allow the boats to be launched, the magnets 27 are energized and attract the inner ends of the latches 24 to pull them up against the action 35 of the springs 26, and the other end out of operative engagement with the booms. The booms are secured to the side or upper works of the ship by chains 27^a, secured to springs 27^b, which latter are secured to the 40 side or upper works of the ship, and act as shock absorbers when the boats are launched. The brake mechanism for the hoisting motors, comprises brake levers 175, and brake shoes 176, a unit for each hoisting 45 motor, the brake shoes being applied by means of stiff coil springs 177, and released by means of magnets, designated on the wiring diagram of Fig. 8, 96, 96', 96'', it being understood, of course, that there is 50 a magnet to each brake unit. The circuits for the brake magnets are in series with the magnets 27, and also with the hoisting motors, so that when the magnets 27 are energized to launch the boats, the brakes 55 will be lifted to permit the boats to over-haul the motors 23, and when the motors 23 are energized to hoist the boats, the brake magnets will again be energized to release the brake shoes, so that the motors 23 may 60 rotate.

Reversing switch 28, and switch 40 are provided, which control the circuits of all the hoisting motors 23, and in addition I have provided independent switches, 37, 37', 37'', 65 for each of the motors 23 (three having been

shown on the wiring diagram for the sake of simplicity), so that the motors 23 may be controlled as a unit or individually. In addition to the switches just mentioned, I have provided reversing switches 32, 32', 32'', 70 for each of the hoisting motors, by means of which the circuit of any one of the hoisting motors may be controlled without disturbing the circuits of the others. For instance, if it were desired to lift any one 75 of the auxiliary boats 2, the switch 37 could be left closed, and all the others opened, and that particular boat could then be hoisted without disturbing the others. To control the circuits of the magnets 27, 80 I have provided a main switch 61, and independent switches, designated on the wiring diagram, 62, 62', 62'', and with these latter all closed, closure of the switch 61 will energize the magnets 27 simultaneously. Of course, if it is desired to hold one magnet energized and deenergized all the others, or vice versa, in the latter event it being desired to have a boom 17 held against the side of the ship to replace one of the 85 boats, the switch 62, for instance, could be opened, and the other independent switches 62', 62'', etc., left closed, and closure of the switch 61 would have no effect on the magnet 27 controlled by the switch 62; in other words the boom 17 controlled thereby would still be retained in elevated position against the side of the ship. The circuits for the propelling motors 8 are controlled by means of main switch 63 and independent switches 64, 64', 64''. With all the 90 switches closed, all the propelling motors 8 will rotate, but should it be desired to hoist one of the boats, for instance, the independent switch controlling that particular boat's propelling motor could be left open, so that its motor would stop, while the boat was being hoisted. The circuits of the magnets 3 are controlled by a main switch 65, and auxiliary switches 66, 66', 66'', 100 105 All the magnets, therefore, may be energized simultaneously, or independently, as desired. Each pair of magnets 3 carried by each boat, is shown in series, but it is to be understood that if desired they could 110 be just as well connected in parallel.

Assuming now that the boats 2 are out of the water, with their individual motors 8 standing still, and their magnets 3 deenergized, and the latches 24, under the action 120 of the springs 26, holding the booms in place against the side of the ship; the brake magnets at this time will be deenergized, so that the brakes will be on the motors 23. We will assume now that it is desired to 125 launch the boats. To do this, it is necessary to magnetize the magnets 27, and also energize the brake magnets.

The circuits for the magnets 27 may be traced as follows: for the magnet 27 at the 130

right hand side of Fig. 8: from the plus main, conductors 29, 90, 91, 67, 84, 68, magnet 27, conductor 69, switch 62, conductors 70, 83, 71, switch 61, conductors 72, 43, 94, 95, and out of the minus side of the line. Circuit for the magnet 27 at the left hand side of Fig. 8: from the plus main, conductors 29, 90, 91, 67, 84, 73, 85, 87, 88, 74, magnet 27, conductor 75, switch 62', conductors 10 76, 77, 89, 81, 82, 83, 71, switch 61, conductors 72, 43, 94, 95, to the minus side of the line. Circuit for the magnet 27 at the bottom of Fig. 8: from the plus main, conductors 29, 90, 91, 67, 84, 73, 85, 78, through the magnet 27, conductor 79, switch 62'', conductors 80, 81, 82, 83, 71, switch 61, conductors 72, 43, 94, 95, to the minus side of the line. It will be seen that the current for all these magnets passes through the 15 switch 61. The inner ends of the latches 24, now that the magnets 27 are energized, will be drawn up against the action of the springs 26, to release the booms 17.

At this time current will also pass 20 through the brake magnets indicated on the wiring diagram, 96, 96', 96'', to release the brakes B, to allow the weight of the boats to overhaul the hoisting motors 23. These 25 circuits for the brake magnets may be traced as follows: from the plus main, conductors 29, 90, 91, 67, 97, through the magnet 96, conductors 98, 71, switch 61, conductors 72, 43, 94 and 95, to the minus side of the line, to lift the brake connected with 30 the motor 23 at the right hand side of Fig. 8. Circuit for brake magnet 96': from the plus main, conductors 29, 90, 91, 67, 84, 73, 85, 87, 99, brake magnet 96', conductors 100, 89, 81, 82, 83, 71, switch 61, conductors 72, 43, 94 and 95, to the minus side of the line, to lift the brake from the motor 23 at the left hand side of Fig. 8. Circuit for the 35 brake magnet 96'': from the plus main, conductors 29, 90, 91, 67, 84, 73, 101, brake magnet 96'', conductors 102, 82, 83, 71, switch 61, conductors 72, 43, 94, 95, to the minus side of the line, to lift the brake from the motor 23 at the bottom of Fig. 8. The 40 brake magnets now all being energized, the boats will overhaul the hoisting motors and descend into the water. So soon as the boats are in the water, the switch 61 may be opened, and the circuits of magnets 27 and the brake magnets opened. It is to be 45 understood that it is not necessary to open the switch 61 at this time, as it may be desired to have the boats take up a position some distance from the ship, in which case it will be necessary to leave the brake circuits closed, so that the motors 23 may be 50 overhauled still more. If now the switches 63 and 65 controlling the circuits of the propelling motors 8, and the magnets 3, respectively, be closed, the motors and magnets will be energized. Circuit for the 55

motor 8 at the right hand side of Fig. 8: from the plus main, conductors 29, 90, 103, 104, through the motor 8, conductor 105, switch 64, conductors 106, 107, switch 63, which is now closed, conductors 108, 94 and 95, to 60 the minus side of the line. Circuit for the motor 8 at the left hand side of Fig. 8: from the plus main, conductors 29, 90, 103, 109, 115, 112, motor 8, conductor 111, switch 64', conductors 110, 113, 114, 107, switch 63, conductors 108, 94 and 95, to the minus side of the line. Circuit for the motor 8 at the bottom of Fig. 8: from the plus main, conductors 29, 90, 103, 109, 118, motor 8, conductor 117, switch 64'', conductors 116, 114, 80 107, switch 63, conductors 108, 94 and 95, to the minus side of the line. The circuits for the magnets 3 at this time may be traced as follows: Circuit for the magnets 3 at the right hand side of Fig. 8: from the plus 85 main, conductors 29, 119, 120, magnet 3, conductor 121, through the other magnet 3 attached to the same boat, conductor 122, switch 66, conductors 123, 124, switch 65, conductors 125, and 95, to the minus side of 90 the line. Circuit for the magnets 3 at the left hand side of Fig. 8: from the plus main, conductors 29, 119, 126, 127, 128, magnet 3, conductor 129, magnet 3, attached to the same boat, conductor 130, switch 66', 95 conductors 131, 132, 133, 124, switch 65, conductors 125 and 95, to the minus side of the line. Circuit for the magnets 3 at the bottom of Fig. 8: from the plus main, conductors 29, 119, 126, 127, magnet 3, conductor 100 128, magnet 3, conductor 129, switch 66'', conductors 130, 133, 124, switch 65, conductors 125, 95, to the minus side of the line.

The apparatus as so far described, is now 105 in full operation, with the boats in the water and being propelled by their respective motors. The rudder in each boat, in practice, would have been set at the proper angle to cause the boats to assume a position at some distance from the side of the ship, 110 to form a protecting barrier about her. The chains 5 and 5^a being attached directly to the magnets 3 will also be magnetized at this time.

Assuming now, that it is desired to hoist 115 all of the boats 2: The switches 63 and 65 will be opened, thus opening the circuits of the propelling motors 8 and the magnets 3. A switch 40 controlling the circuits of the hoisting motors will now be closed and 120 circuits closed thereby to the various hoisting motors 23, and at the same time to the brake magnets, so as to take the brakes off the motors. Circuit for the hoisting motor 23 at the right hand side of Fig. 8: from the 125 plus main, conductors 29, 90, 91, 134, reversing switch 28, conductor 41, switch 40, conductors 135, 39, 38, switch 37, conductor 36, one side of switch 32, conductor 35, motor 23, conductors 34, 33, other side of the 130

switch 32, conductors 31, 136, 137, 42, other side of the switch 28, conductors 138, 43, 94 and 95 to the minus side of the line. The brake magnet 96 will receive current at 5 this time also, its circuit being traced as follows: from the plus main, conductors 29, 90, 91, 134, one side of switch 28, conductor 41, switch 40, conductors 135, 140, 97, through the brake magnet 96, conductors 10 98, 141, 137, 42, other side of switch 28, conductors 138, 43, 94 and 95, to the minus side of the line. The circuit for the motor 23 at the left hand side of Fig. 8: from the plus main, conductors 29, 90, 91, 134, one 15 side of switch 28, conductor 41, switch 40, conductors 135, 39, 142, 44, 148, 144, 45, switch 37', conductor 47, one side of switch 32', conductor 49, motor 23, conductors 50, 51, other side of switch 32', conductors 52, 20 145, 53, 150, 146, 136, 137, 42, other side of switch 28, conductors 138, 43, 94, 95, to the minus side of the line. The circuit at this time is also closed to the brake magnet 96' for this motor: from the plus main, conductors 25 29, 90, 91, 134, switch 28, conductor 41, switch 40, conductors 135, 39, 142, 44, 148, 143, 99, brake magnet 96', conductors 100, 149, 53, 150, 146, 136, 137, 42, other side of switch 28, conductors 138, 43, 94 and 95 to 30 the minus side of the line. The circuit for the motor 23 at the bottom of Fig. 8 is as follows: from the plus main, conductors 29, 90, 91, 134, one side of switch 28, conductor 41, switch 40, conductors 135, 39, 142, 44, 54, switch 37'', conductor 56, one side of switch 32'', conductor 58, motor 23, conductors 59, 60, other side of switch 32'', conductors 61, 150, 146, 136, 137, 42, other side of switch 28, conductors 138, 43, 94 and 95, 35 40 to the minus side of the line. The brake magnet 96'' at this time receives current as follows: from the plus main, conductors 29, 90, 91, 134, one side of switch 28, conductor 41, switch 40, conductors 135, 39, 142, 162, 45 101, through the brake magnet 96'', conductors 102, 163, 146, 136, 137, 42, other side of switch 28, conductors 138, 43, 94, and 95 to the minus side of the line. The brakes for the motors 23 having now been 50 55 lifted, and the circuits closed for the motors, the latter will hoist the boats, until the stop ball or other member 165 carried by each hoisting cable, engages the end of telescoping arm 166 of the booms 17, at which time the arms 166, having now been telescoped, 60 65 will be swung about their pivots 18, and up against the side of the ship, the ends of the booms snapping by the latches 24, so that when the circuits of the hoisting motors 23 are again opened, the booms will be held in position.

At any time, while the boats are in the water, should it be desired to hoist one of them without disturbing the others, it is merely necessary to open the switches 37, etc., of

such boats as it is desired to leave in the water, then by closing the switch 40 the other boats will be hoisted.

Having thus described my invention, and without limiting myself to the precise construction and arrangement of parts herein shown and described, what I claim as new and desire to secure by Letters Patent of the United States is:—

1. In apparatus for protecting ships, the 75 combination of a plurality of units carried by the ship, means for launching said units from the ship simultaneously or individually, means connecting the units, the units and connecting means when launched forming a protecting barrier about the ship.

2. In apparatus for protecting ships, the 80 combination of a plurality of units carried by the ship, means for launching said units from the ship, means connecting the units, 85 the units and connecting means when launched forming a protecting barrier about the ship, and mechanism for controlling the launching mechanism whereby the units may be launched simultaneously or only 90 such units as may be desired.

3. In apparatus for protecting ships, the 95 combination of a plurality of units carried by the ship, means for launching said units from the ship simultaneously or individually 100 as desired, means connecting the units, the units and connecting means when launched forming a protecting barrier about the ship, propelling mechanism for each unit, and a single control for the propelling mechanism. 105

4. In apparatus for protecting ships, the 110 combination of a plurality of units carried by the ship, booms by which the units are connected to the ship, means connecting the units, and means controlling the operation 105 of said booms whereby all the units may be launched simultaneously or individually as desired.

5. In apparatus for protecting ships, the 115 combination of a plurality of units carried by the ship, means connecting the units, means for launching the units so that they and their connecting means form a protecting barrier about the ship, mechanism for hoisting the units out of the water, mechanism 120 for controlling the hoisting means to hoist all the units simultaneously, and separate controlling means whereby any desired unit may be hoisted without disturbing the others.

6. In apparatus for protecting ships, the 125 combination of a plurality of units carried by the ship, means connecting the units, means for launching the units so that they and their connecting means form a protecting barrier about the ship, magnets carried by each unit and extending into the water when the units are in the water, some of the connecting means for the units being attached to the said magnets, and means for 130

energizing said magnets and connecting means.

7. In apparatus for protecting ships, the combination of a plurality of units carried by the ship, means connecting the units to each other, means for launching the units so that they and their connecting means form a protecting barrier about the ship, magnets carried by each unit and extending into the water when the units are in the water, and means operative from the ship for controlling the energization of said magnets.

8. In apparatus for protecting ships, the combination of a plurality of units carried by the ship, means connecting the units to each other, means for launching the units so that they and their connecting means form a protecting barrier about the ship, magnets carried by each unit and extending into the water when the units are in the water, and means operative from the ship for energizing said magnets simultaneously.

9. In apparatus for protecting ships, the combination of a plurality of units carried by the ship, means connecting the units to each other, means for launching the units so that they and their connecting means form a protecting barrier about the ship, magnets carried by each unit to which the connecting means are attached, these magnets extending into the water when the units are in the water, and means for selectively controlling the energization of said magnets whereby the magnets carried by any number of the units may be energized without energizing the others.

10. In apparatus for protecting ships, the combination of a plurality of units carried by the ship, connecting means therefor, means for launching the units so that they and their connecting means form a protecting barrier about the ship, hoisting mechanism for raising and lowering the units, brake mechanism therefor, and a single control for said brakes, whereby the units may be raised or lowered simultaneously.

11. In apparatus for protecting ships, the combination of a plurality of units carried by the ship, connecting means therefor, means for launching the units so that they and their connecting means form a protecting barrier about the ship, hoisting mechanism for raising and lowering the units, brake mechanism therefor, booms attached to the units, said booms being actuated in one direction by the hoisting mechanism, means for holding the booms against the side of the ship when the units are not in

use, and a single control for the holding means and the brake mechanism for the hoisting mechanism.

12. In apparatus for protecting ships, the combination of a plurality of units carried by the ship, connecting means therefor, hoisting mechanism from which the units are suspended, brake mechanism for said hoisting mechanism, and means controlling said hoisting mechanism, whereby the units will be lowered by gravity and hoisted by power, means for maintaining the units in hoisted position and means controlling said brake mechanism whereby the brakes will be lifted whenever the means for maintaining the units in hoisted position are actuated to inoperative position, and when it is desired to hoist the units.

13. In apparatus for protecting ships, the combination of a plurality of units carried by the ship, connecting means therefor, pivoted booms to which the units are attached, hoisting mechanism for said units and booms, means for maintaining the booms in position against the side of the ship when the units are out of the water, brake mechanism for the hoisting mechanism, and means for controlling the brake mechanism and the means for maintaining the booms in position against the side of the ship simultaneously, and separate means for controlling the brake mechanism independently of the means for maintaining the booms in position.

14. In apparatus for protecting ships, the combination of a plurality of units carried by the ship, detachable means connecting the units, magnets carried by the units, detachable means connecting the magnets carried by each unit, and means for energizing said magnets and connecting means simultaneously, the units together with the magnets and connecting means forming a protecting barrier about the ship.

15. In apparatus for protecting ships against torpedo attack, the combination of a plurality of units carried by the ship, launching mechanism therefor, means connecting the units to each other, propelling mechanism for each unit, booms to which the units are attached, means for holding said booms in position, magnets carried by each unit, means for releasing said booms when it is desired to launch the units, and means for energizing said magnets and starting up the propelling mechanism for the various units simultaneously.

In testimony whereof I have hereunto set my hand.

EDWARD A. SMITH,
